UNITED STATES PATENT OFFICE.

GEORGE B. CALHOUN, LEWIS WHITE, AND LEMON HAYES, OF WEST FRANKFORT, ILLINOIS; SAID LEMON HAYES AND SAID GEORGE B. CALHOUN ASSIGNS TO ARTHUR WILLIAMS AND BERT PETERSON, BOTH OF WEST FRANKFORT, ILLINOIS.

FUEL ECONOMIZER.

Application filed July 23, 1924. Serial No. 727,776.

To all whom it may concern:

Be it known that we, GEORGE B. CALHOUN, LEWIS WHITE, and LEMON HAYES, citizens of the United States, residing at West 5 Frankfort, in the county of Franklin and State of Illinois, have invented new and useful Improvements in Fuel Economizers, of which the following is a specification.

Our present invention has reference to an 10 attachment for an internal combustion motors.

Our object is the provision of a valve controlled conduit between the breather pipe and the intake manifold of an internal combustion engine whereby the vapors from the oil in the engine will be caused to commingle with the gaseous fluid directed through the carburetor, and thereby increase the volatility of the mixture to produce a more perfect combustion, and also 20 to economize the fuel consumption of the engine.

To the attainment of the foregoing and other objects which will present themselves 25 as the nature of the invention is better understood, reference is to be had to the drawings which accompany and which form part of this application.

In the drawings:

30 Figure 1 is a side elevation of an internal combustion engine illustrating the application of the improvement thereon.

Figure 2 is a side elevation of the member employed in lieu of the ordinary cap for 35 the breather pipe of the engine.

Figure 3 is a top plan view thereof.

Figure 4 is a sectional view approximately on the line 4—4 of Figure 3.

40 Figure 5 is a fragmentary sectional view through the conduit or vapor conducting pipe to illustrate the valve controlling the passage therethrough.

In the drawings the numeral 1 broadly 45 designates an internal combustion engine, 2 the intake manifold therefor, and 3 the breather pipe.

In lieu of the usual cap for the breather pipe we make use of a tubular casting 4 having its outer portion thickened, as at 5, 50 and its outer wall, below the thickened portion flared for tight frictional engagement with the breather pipe 3, when inserted therein. The tubular member 4 has its opened top closed by a plate 6. This plate

is in the nature of a combined valve and a 55 closure which is movable to permit of oil being fed into the breather pipe through the tubular member 4. The plate 5 has passed therethrough a headed screw 7 that also enters the thickened portion of the 60 tubular member 4. A spring 8 is arranged around the shank of the bolt 7 to contact with the plate 6. Diametrically opposite the bolt 7 the plate has passed therethrough the shank of a headed member 9. Preferably 65 this member is spring influenced toward the plate and the shank thereof is designed to enter a notch 10 in the thickened or shouldered portion 5 of the tubular member 4. By this arrangement it will be 70 noted that the plate is permitted a limited longitudinal movement on the tubular member 4, incident to excessive expansion or pressure of the vapor from the oil in the engine. Also by this arrangement it will 75 be noted that the headed member 9 may be moved to bring its shank out of the notch 10 in the portion 5 of the member 4 so that the said plate 6 may be swung on the bolt 7 to uncover the member 4 and permit of oil 80 being inserted into the breather pipe.

On one side of the thickened portion 5 of the member 4 there is an air inlet opening 11 normally closed by a valve 12 which is influenced by a spring 13. On the opposite side of the shoulder 5 there is a second opening which is threaded and which has screwed therein one end of a conduit or pipe 13. The pipe 13 has its free end connected to a valve casing 14, the passage 85 through the casing being controlled by a plug valve 15. To the handle of the valve there is connected the bifurcated end of a rod 16. The rod passes through the dash and through the instrument board of the 90 automobile propelled by the motor 1. The free end of the rod is headed, as at 17, and the said head may be arranged over a dial or indicator plate 18.

By turning the rod to open the valve it 100 will be apparent that the vapors from the oil in the engine will pass through the pipe 13 into the manifold 2 and mix with the gases delivered therethrough into the engine cylinders. It is to be noted that the valve casing 3 is screwed through an opening in the manifold 2 at the juncture of the straight 105 and angular branches thereof so that the

vaporized fuel from the breather pipe will be caused to mix with the gases passing through the manifold in a manner whereby the said mixture will enter all of the cylinders. The valve 12 is automatically opened to permit air passing through the port 11 and through the tubular member 4 into the breather pipe when excess vacuum is created in the crank case.

10 It is believed that the simplicity and advantages of my improvement will be perfectly apparent to those skilled in the art to which such inventions relate, and while we have herein set forth a satisfactory embodiment of our improvement, it is to be understood that such changes therefrom as fairly fall within the scope of the claim may be resorted to when desired.

Having described the invention we claim:

20 In a device for the purpose set forth and in combination with an internal combustion engine including the intake manifold

and the breather pipe therefor, of a means for conducting the vapor from oil in the breather pipe to the intake manifold at the juncture of the straight and angular branches thereof comprising a tubular member having an outer shouldered portion received and frictionally engaging with the breather pipe, a pivoted plate providing a closure for the tubular member, spring means normally influencing the plate toward the tubular member, means for latching the plate on the tubular member, a normally closed spring influenced air inlet pipe for the tubular member, a vapor conducting pipe between the tubular member and the manifold, a valve controlling the passage through said pipe and an operating rod for the valve.

In testimony whereof we affix our signatures.

GEO. B. CALHOUN.
LEWIS WHITE.
LEMON HAYES.
